CLAIM

The ornamental design for augmented reality glasses, as shown and described.

DESCRIPTION

FIG. 1 is an upper-front-left perspective view of the augmented reality glasses, showing our new design;

FIG. 2 is an upper-rear-right perspective view thereof;

FIG. 3 is a rear view thereof;

FIG. 4 is a front view thereof;

FIG. 5 is a right view thereof;

FIG. 6 is a left view thereof;

FIG. 7 is a top view thereof; and,

FIG. 8 is a bottom view thereof.

The broken lines in the drawings depict portions of the augmented reality glasses that form no part of the claimed design.

1 Claim, 6 Drawing Sheets
